United States Patent Office

Des. 223,780
Patented June 6, 1972

223,780

MICRO FICHE READER

Peter T. Quinn, Littleton, Colo., assignor to Honeywell Inc., Minneapolis, Minn.

Filed July 23, 1970, Ser. No. 24,089

Term of patent 14 years

Int. Cl. D16—03

U.S. Cl. D61—1

FIG. 1

FIG. 2

FIG. 1 is a front perspective view of the micro fiche reader showing my new design;

FIG. 2 is a rear perspective view thereof.

The bottom surfaces are plain and unornamented.

I claim:

The ornamental design for a micro fiche reader, as shown and described.
